UNITED STATES PATENT OFFICE

1,927,869

AIR CONDITIONING AND CIRCULATING
UNIT

Sewell H. Downs, Kalamazoo, Mich.

Application May 2, 1932. Serial No. 608,766

18 Claims. (Cl. 183—23)

The objects of my invention are:

First, to provide an improved air conditioning and circulating unit suitable for use in a room.

Second, to provide such a unit that can be manufactured in sections in which are installed various units for conditioning air which sections are interchangeable or may all be installed for use when desired or may be added as conditions demand.

10 Third, to provide such a unit that maintains the various conditioning means at substantially constant conditions and by-passes portions of the air around said units to provide the proper condition of the air that is circulated in the room.

15 Fourth, to provide such a unit that uses recirculated air or fresh air or both.

Fifth, to provide such a unit that is compact and has all of the necessary conditioning means 20 in one casing.

Sixth, to provide such a unit with special dampers.

Seventh, to provide a damper construction especially adapted for use in such by-passing units.

25 Further objects and advantages of construction and operation will appear from the description to follow. A preferred embodiment of my invention is illustrated in the accompanying drawings, in which:

30 Fig. 1 is a section through the fully equipped conditioner.

Fig. 2 is an end elevation partially in section showing the unit with only one conditioning section in place.

35 Fig. 3 is a side elevation partly in section of one end of the unit.

Fig. 4 is a detail sectional view of the damper controls.

40 Fig. 5 is a detail sectional view taken on line 5—5 of Fig. 4.

Fig. 6 is a detail perspective view of the damper blade.

The parts will be identified by their numerals of reference which are the same in all the views.

45 My improved air circulating and conditioning unit is represented at 1, having a casing 2 comprising a series of separable sections 3, 4, 5, 6, 7, 8, 9 adapted to be fitted together to form the single casing 2 having an open bottom. At the 50 upper and lower edges of the sections are flanges 10 adapted to engage similar flanges on the other sections. This arrangement makes possible the use of any or all of said sections and each is adapted to be fastened to each other section so 55 that they may be arranged in any order as de-

sired. The flanges are fastened together by through bolts 11. The casings are supported on a base 12 having legs 13. In the top section are installed a series of centrifugal fans 14 of any desired construction having their outlets 15 positioned to discharge air into the room. The outlets 15 may be directed to any portion of the room as desired. The fans 15 are all run on a single shaft 16, as is shown in Fig. 3, which may be driven by any suitable motor not here illustrated.

At the bottom of the casing may be a filter 17. I have merely indicated the filter unit conventionally. It may be of any desired construction of paper, fiber, wire mesh or spun glass, depending upon the use to which the device is to be put.

In section 8 above the filter is a heat exchange element 18 which is here shown as a header with circulating coils adapted to circulate either a hot or a refrigerated fluid depending upon whether it is desired to heat or cool the air. Depending from the lower edges of heater 18 are flanges or baffles 19. The heater is spaced from the side walls of the section 8 to form by-passes 20.

Immediately below the section 8, I illustrate my improved by-pass dampers adapted to control the flow of air through the heat exchange element 18 and the by-passes 20 to either close off the flow of air through said by-passes or said heater as desired or to proportion the flow of air between them. My improved damper construction comprises pivoted blade supports 21 pivoted at points 22 having counterweights 23 and carrying blades 24. The blades 24 here shown are curved and this construction is desirable because when the dampers are placed in proximity to the flanges 19 the blades are kept substantially the same distance from the flanges in whatever position they are set and prevent passage of air between the blades and the flanges, or from the heat exchange element to the by-passes. If desired, a straight blade could be used. Depending from blades 24 are flanges 25 so positioned that when the dampers which are placed to control the flow of air through by-passes 20 are in a position to close by-passes 20, the flanges 25 engage the flanges 19 to assure a complete closure of the by-passes. These flanges act as stiffening elements to maintain the blades 24 in the proper shape and if desired similar flanges 25' may be supplied on the opposite side of blade 24 to assist in the stiffening.

Intermediate the pair of by-pass dampers is a straight blade pivoted damper having a blade 26

- supported on a circular support 27 and adapted to assist in closing off the flow of air through heat exchange element 18 and when the by-pass dampers are in position to close off the flow of air through heat exchange element 18 and allow it to flow through the by-passes 20, the flanges 25 on the by-pass dampers engage opposite edges of the blade 26 of the straight blade damper. The by-pass dampers and the straight blade damper are connected for simultaneous operation by links 28 and are provided with control means comprising a shaft 29, here shown as adapted to rotate damper 26, having thereon a lever 30 operating outside of section 9 and having a control segment 31. On the shaft or rod 29 is a shaft 32 extending perpendicularly from said shaft 29 and having thereon a sliding adjustable counterweight 33, the position of which on said rod 32 is maintained by a set screw 34.
- 20 This damper unit can be placed either side up and on either side of the heat exchange element, and the baffles or flanges 19 extending from heat exchange element 18 extend from the side of the said element adjacent the damper.
- 25 In section 4, I have illustrated an identical damper in the reverse position controlling the flow of air through a heat exchange unit 35, which may be either a cooler or heater, but which is illustrated here in section 5 to be used as a re-heater to reduce the relative humidity of air after it has been cooled and saturated by sprays later to be described. This heat exchange unit 35 is spaced from the walls of section 5 to form by-passes 36 similar to by-passes 20 and the dampers shown in section 4 operate in every respect identically with those shown in section 9. If it is desired to condition or humidify the air, a section 7 having spray heads 37 therein can be used.
- 40 Fluid is supplied for sprays 37 and usually will be water, although it may be brine or any suitable fluid. The fluid may be supplied from a conditioning unit which is not here shown, but is conventional for either heating or refrigerating the fluid or it may be tap water or untreated fluid from any source or it may be fluid re-circulated from the pan 39, which may or may not be re-heated or refrigerated before recirculation through sprays 37.
- 45 When these sprays are used and it is desired to eliminate entrained water from the air, a section such as section 6 with eliminator plates 38 of conventional type may be installed between the sprays and the fan. When the sprays are used, or the unit is being used for cooling, I provide a pan 39 below the unit to collect any moisture falling therefrom.
- 50 The unit may be used for merely re-circulating air within the room, or it may be arranged to take air from outside or from another source such as 40, or it may be arranged to take air from within the room and from the outside in varying proportions or selectively as desired. For this purpose, the unit is arranged with a connection shown at 41 to an aperture 42 leading to the other source of air or to the outside air, and having louvres 43 therein and a pivoted straight blade damper construction shown at 44 adapted to cut off the flow of air therethrough. The ends 60 of the unit are, under such circumstances, sealed and the side of the unit not connected by 41 to the other source of air is provided with a damper construction 45 similar to that shown at 44 and the dampers are connected with link 46 for simultaneous movement to selectively cut off one or

the other source of air or to proportion the flow of air from both sources.

I have illustrated my unit with a hand control but, as is obvious, it can be used with any automatic or hand control. The proportioning of the air passing through the heat exchange unit 18 or 35 and the by-passes 20 or 36 can be controlled by thermostats or humidistats placed either in the outlet 15 of the fan or at a place in the room, or in the inlet to the unit casing or at the inlet from the outside or other source, or within the unit as may be desired. 80 85

In conjunction with the control of the condition of the air by proportioning the air passing through the heat exchange units and the by-passes or for use entirely without the proportioning to determine the final condition of the air coming from the apparatus, controls may be provided to control the temperature or condition of the heat exchange units and the sprays. Thermostats or humidistats located as above indicated or in any of such locations may automatically control the temperature of the heat exchange units or the sprays or might control the amount of fluid running through sprays 37 to determine 90 95 the exact amount of fluid available to affect the humidity of the air coming from the unit.

In operation, the fans 15 create a flow of air through the casing 2. The heat exchange unit 18 may be set to maintain a constant temperature. This may be done by the use of steam at a constant pressure, or, if cooling is desired, a constant pressure evaporation within the unit 18 may be provided. Other means of maintaining the temperature constant can also be used. The 100 use of by-pass dampers 21 and the blade 26 of the straight blade damper determines the proportion of air passing through the apparatus that passes through the unit 18. By gauging this proportion properly, the final temperature of the 105 air beyond unit 18 is determined. A similar use of the heat exchange unit 35 and the dampers in section 4 again gives control of the final temperature of the issuing air. If the dampers are not used to proportion the air passing through the 110 heat exchange units 18 and 35, the temperature of the heat exchange units may be varied as above set forth and it is possible to either heat or refrigerate the fluid issuing from sprays 37 to change the temperature of the issuing air or to determine 115 its humidity.

The sprays 37 in section 7 may be used only to wash the air or may be used to saturate or partially saturate the air by means of the sprays or to cool or heat the air. This may be done 120 either in conjunction with heat exchange units 18 and 35 or not as conditions require. When the air has passed through the sprays it passes through the eliminators to remove entrained water. 125

When the sprays 37 are used to affect the humidity of the air passing through the casing, heat exchange unit 35 is usually used as a heater to raise the temperature of the air after it has been sprayed and impart to it the proper relative humidity. The unit 35 may be run at a constant temperature and the final temperature may be obtained by proportioning the air by-passed to the air passing through the unit 35 or the unit may be run with its temperature varied according to the demands in the room to be conditioned. 130 140 145

If the apparatus is used in cold weather with outside air entering as at 40, it is desirable to have a heat coil located in the duct 41 or at the opening 40 to temper the air before it reaches the 145

apparatus, to prevent freezing of the fluid in the pan 39 or elsewhere throughout the system and to reduce the demands on the rest of the apparatus. Such a tempering coil is conventional and I have not here illustrated it. The control for the temperature of this heating coil can be manual and can be thermostatically governed by the temperature of the outside air or by the temperatures in the room.

10 I have described my invention in the embodiment preferred by me, but wish to claim the same broadly as well as specifically, as pointed out in the appended claims.

Having thus described my invention, what I 15 claim as new and desire to secure by Letters Patent is:

1. In a unit air conditioner and circulator, the combination of a casing, a heat exchange element spaced from two walls of said casing to form 20 by-passes, flanges on said element adjacent said by-passes, and means for controlling the flow of air through said by-passes and said heat exchange element comprising a pair of dampers having curved blades on pivoted supports having counter- 25 weights adapted to close said by-passes, a centrally disposed damper adapted to partially close off said element, and flanges on said curved blades adapted in one position to engage said first mentioned flange and in another position to engage 30 the blade of said centrally disposed damper, links connecting said dampers for simultaneous movement, and means for operating said dampers.

2. In an air conditioning and circulating unit, the combination of a casing having an opening 35 for the admission of air, a heat exchange element spaced from the walls of said casing to form a pair of by-passes, flanges on said element adjacent said by-passes, and means for controlling the proportion of the volumes of air flowing 40 through said by-passes and said element comprising a pair of by-pass dampers having curved blades with pivoted counterweighted supports therefor adapted in one position to cut off the flow of air through said by-passes and in another 45 position to partially cut off the flow of air through said element, a pivoted damper adapted to engage said by-pass dampers in said second mentioned position to cut off the flow of air through 50 said element, a flange on each of said by-pass dampers adapted to engage one of said first mentioned flanges when said by-pass dampers are in the first mentioned position, means connecting 55 said dampers for simultaneous movement, and an adjustable counterweight for all of said dampers.

3. In an air conditioning and circulating unit, the combination of a casing having an opening for the admission of air, a heat exchange element spaced from the walls of said casing to form 60 a pair of by-passes, flanges on said element adjacent said by-passes, and means for controlling the proportion of the volumes of air flowing through said by-passes and said element comprising a pair of by-pass dampers having blades 65 adapted in one position to cut off the flow of air through said by-passes and in another position to partially cut off the flow of air through said element, a damper adapted to engage said by-pass dampers in said second mentioned position to cut 70 off the flow of air through said element, a flang on each of said by-pass dampers adapted to engage one of said first mentioned flanges when said by-pass dampers are in the first mentioned position, and means connecting said dampers for simultaneous movement.

4. In an air conditioning and circulating unit, the combination of a casing having an opening for the admission of air, a heat exchange element spaced from the walls of said casing to form a pair of by-passes, and means for controlling the proportion of the volumes of air flowing through said by-passes and said element comprising a pair of by-pass dampers having curved blades with pivoted counterweighted supports therefor adapted in one position to cut off the flow of air through said by-passes and in another position to partially cut off the flow of air through said element, a pivoted damper adapted to engage said by-pass dampers in said second mentioned position to cut off the flow of air through said element, and means connecting said dampers for simultaneous movement.

5. In an air conditioning and circulating unit, the combination of a casing having an opening for the admission of air, a heat exchange element spaced from the walls of said casing to form a pair of by-passes, and means for controlling the proportion of the volumes of air flowing through said by-passes and said element comprising a pair of by-pass dampers having curved blades with pivoted counterweighted supports therefor adapted in one position to cut off the flow of air through said by-passes and in another position to partially cut off the flow of air through said element, a pivoted damper adapted to engage said by-pass dampers in said second mentioned position to cut off the flow of air through said element.

6. In an air conditioning and circulating unit, the combination of a casing having an opening 110 for the admission of air, a heat exchange element spaced from the walls of said casing to form a pair of by-passes, flanges on said element adjacent said by-passes, and means for controlling the proportion of the volumes of air flowing 115 through said by-passes and said element comprising a pair of by-pass dampers having curved blades with pivoted counterweighted supports therefor adapted to swing said blades in arcs of circles in cooperating relation with said flanges, 120 and means connecting said dampers for simultaneous movement.

7. In an air conditioning and circulating unit, the combination of a casing having an opening for the admission of air, a heat exchange element 125 spaced from the walls of said casing to form a pair of by-passes, flanges on said element adjacent said by-passes, and means for controlling the proportion of the volumes of air flowing through said by-passes and said element comprising a pair of by-pass dampers each adapted in one position to cut off the flow of air through a by-pass and in another to partially cut off the flow of air through said heat exchange element, and a flange on each of said by-pass dampers adapted 130 to engage one of said first mentioned flanges.

8. In a unit air conditioner and circulator, the combination of a vertically disposed casing having an air inlet at the bottom, a filter for air entering the casing, a heat exchange element 140 within and spaced from said casing to form by-passes, interconnected dampers for controlling the volume of air flowing through said by-passes and said element, spray means and eliminators in said casing, a second heat exchange element 145 within and spaced from said casing to form by-passes and additional interconnected dampers for controlling the volume of air flowing through said second mentioned by-passes and said second heat exchange element.

9. In a unit air conditioner and circulator, the combination of a vertically disposed casing having an air inlet at the bottom, a heat exchange element within and spaced from said casing to form by-passes, interconnected dampers for controlling the volume of air flowing through said by-passes and said element, spray means and eliminators in said casing, a second heat exchange element within and spaced from said casing to form by-passes, and additional interconnected dampers for controlling the volume of air flowing through said second mentioned by-passes and said second heat exchange element. 80
10. In a unit air conditioner and circulator, the combination of a base having an opening for admission of air, a separable heat exchange section having a heat exchange element spaced from the wall thereof to form a by-pass, a separable damper section having dampers adapted to control the volume of air flowing through said heat exchange element and said by-pass, a separable section having sprays, a separable section having eliminators therein, a second separable heat exchange section having a heat exchange element spaced from the wall thereof to form a by-pass, a second separable damper section having dampers adapted to control the volume of air flowing through said second mentioned heat exchange element and by-pass, all of said separable sections adapted to be placed together to form a casing, and a separable section having means for causing the flow of air through said casing. 85
11. In a unit air conditioner and circulator, the combination of a base having an opening for admission of air, a separable heat exchange section having a heat exchange element spaced from the wall thereof to form a by-pass, a separable damper section having dampers adapted to control the volume of air flowing through said heat exchange element and said by-pass, a separable section having sprays, a separable section having eliminators therein, all of said separable sections adapted to be placed together to form a casing, and a separable section having means for causing the flow of air through said casing. 90
12. In a unit air conditioner and circulator, the combination of a base having an opening for admission of air, a separable heat exchange section having a heat exchange element spaced from the wall thereof to form a by-pass, a separable damper section having dampers adapted to control the volume of air flowing through said heat exchange element and said by-pass, all of said separable sections adapted to be placed together to form a casing, and a separable section having means for causing the flow of air through said casing. 95
13. In a unit air conditioner and circulator, the combination of a base having an opening for admission of air, a separable heat exchange section having a heat exchange element spaced from the wall thereof to form a by-pass, a separable damper section having dampers adapted to control the volume of air flowing through said heat exchange element and said by-pass, all of said separable sections adapted to be placed together to form a casing, and means for causing the flow of air through said casing. 100
14. In a unit air conditioner and circulator, the combination of a base adapted to receive the walls of one of a plurality of separable sections, a plurality of separable sections adapted to fit together to form a casing, at least one section having a heat exchange unit spaced from the wall thereof to form a by-pass, another section having damper means to control the volume of air flowing through said heat exchange element and said by-pass, another section having spray means, and another section having eliminators. 105
15. In a unit air conditioner and circulator, the combination of a base adapted to receive the walls of one of a plurality of separable sections, a plurality of separable sections adapted to fit together to form a casing, one section having a heat exchange unit spaced from the wall thereof to form a by-pass, and at least one other section having damper means to control the volume of air flowing through said heat exchange element and said by-pass. 110
16. In an air conditioning and circulating unit, the combination of a casing having an opening therein for the admission of air, an air conditioning element having walls spaced from the walls of said casing to form a pair of by-passes, and means for controlling the proportion of the volumes of air flowing through said by-passes and said element comprising a pair of by-pass dampers each having pivoted blade supports and a curved blade supported thereon to slide past a wall of said element in cooperating relation thereto, and in a path that is a curved surface passing transversely through the plane of said wall, each blade being adapted in one position to cut off the flow of air through a by-pass and in another position to cut off a portion of the flow of air through said element. 115
17. In an air conditioning and circulating unit, the combination of a casing having an opening for the admission of air thereto, an air conditioning element having a wall spaced from the wall of said casing to form a by-pass, and a damper adapted to control the proportion of the volumes of air flowing through said by-pass and said element comprising pivoted counterweighted blade supports and a curved blade supported thereon to slide past the wall of said element in cooperating relation thereto and in a path that is a curved surface passing transversely through the plane of said wall, said blade being adapted in one position to cut off the flow of air through said by-pass and in another position to cut off a portion of the flow of air through said element. 120
18. In an air conditioning and circulating unit, the combination of a casing having an opening for the admission of air thereto, an air conditioning element having a wall spaced from the wall of said casing to form a by-pass, and a damper adapted to control the proportion of the volumes of air flowing through said by-pass and said element comprising pivoted blade supports and a curved blade supported thereon to slide past the wall of said element in cooperating relation thereto and in a path that is a curved surface passing transversely through the plane of said wall, said blade being adapted in one position to cut off the flow of air through said by-pass and in another position to cut off a portion of the flow of air through said element. 125
19. In an air conditioning and circulating unit, the combination of a casing having an opening for the admission of air thereto, an air conditioning element having a wall spaced from the wall of said casing to form a by-pass, and a damper adapted to control the proportion of the volumes of air flowing through said by-pass and said element comprising pivoted blade supports and a curved blade supported thereon to slide past the wall of said element in cooperating relation thereto and in a path that is a curved surface passing transversely through the plane of said wall, said blade being adapted in one position to cut off the flow of air through said by-pass and in another position to cut off a portion of the flow of air through said element. 130
20. In a unit air conditioner and circulator, the combination of a base adapted to receive the walls of one of a plurality of separable sections, a plurality of separable sections adapted to fit together to form a casing, one section having a heat exchange unit spaced from the wall thereof to form a by-pass, another section having damper means to control the volume of air flowing through said heat exchange element and said by-pass, another section having spray means, and another section having eliminators. 135
21. In a unit air conditioner and circulator, the combination of a base adapted to receive the walls of one of a plurality of separable sections, a plurality of separable sections adapted to fit together to form a casing, one section having a heat exchange unit spaced from the wall thereof to form a by-pass, another section having damper means to control the volume of air flowing through said heat exchange element and said by-pass, another section having spray means, and another section having eliminators. 140

SEWELL H. DOWNS. 145
